(57) **ABSTRACT**

High W-Heels are stylish mobility devices, worn on each foot designed left and right, combining wheeled chassis below attached to fashionable boot above. Their unique three wheeled chassis design, featuring two same sized smaller diameter wheels in front (attached by axle) and a single larger diameter (high) wheel in the back, forms a triangle which provides the user the desirable combined stability of roller skates with the agility of roller blades. This forward leaning (high wheel) design aids momentum and promotes good posture while offering the renowned fashion of a stylish high-heeled demi-boot.

HIGH WHEEL SKATE**TECHNICAL FIELD**

The present invention relates to wheeled skates.

BACKGROUND

Traditional roller skates with a pair of front and rear wheels and inline skates with the wheels provided in a single line are well established. However, the current designs do not provide a fashionable three-wheel design that combines the features of traditional roller skates and inline roller skates.

SUMMARY

The present disclosure provides a novel skate design. A unique three-wheel chassis design is provided that features two same sized smaller diameter wheels in front (connected by axle) and a single larger diameter (high) wheel in the back. This design forms a triangle which provides the user the desirable combined stability of roller skates with the agility of roller blades. This forward leaning (high wheel) design aids momentum and promotes good posture while offering the renowned fashion of a stylish high-heeled demi-boot.

BRIEF DESCRIPTION OF THE DRAWINGS

FIG. 1 is a perspective view of the skate;
 FIG. 2 is a left side view of the left skate;
 FIG. 3 is a chassis configuration without the boot;

DETAILED DESCRIPTION

A high wheeled stylish skate, worn on each foot is provided. As shown in the figures the unique three wheeled chassis design, features two same sized smaller diameter wheels in front (connected by axle) and a single larger diameter (high) wheel in the back. This design forms a triangle which provides the user the desirable combined stability of roller skates with the agility of roller blades. The forward leaning (high wheel) design aids momentum and promotes good posture while offering the renowned fashion of a stylish high-heeled demi-boot.

The invention claimed is:

1. A high wheeled skate for skating comprises:
 a boot for receiving a foot of a user, where a heel portion of the boot is elevated relative to a forward section of the boot;
 two forward wheels connected by axle provided below the forward section, the access of the axle is perpendicular to and equally staddles the lengthwise centerline of the boot;
 a single rear wheel attached directly below the heel portion;
 where the single rear wheel is larger in diameter than the two forward wheels, where the single rear wheel is located on the lengthwise centerline of the boot to a provide a triangular support base.
